Attn:

UNITED STATES PATENT OFFICE.

MARION H. WALKER, OF WHITEHALL, ILLINOIS.

STOCK-CAR.

SPECIFICATION forming part of Letters Patent No. 288,682, dated November 20, 1883.

Application filed August 1, 1883. (No model.)

To all whom it may concern:

Be it known that I, MARION H. WALKER, a citizen of the United States, residing at Whitehall, in the county of Greene and State of Illinois, have invented certain new and useful Improvements in Stock-Cars; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to improvements in stock-cars, and has for its object to so construct the cars that when they are connected to form a train passage-ways may be formed between them, so that the stock can pass from one car 20 to another, to enable the filling of the entire train from one end or from any point desired along the train; and it consists in the construction, combination, and arrangement of the devices hereinafter described and claimed, whereby such results are accomplished.

In the drawings, Figure 1 is a side view of the end sections of two cars connected and constructed according to my invention. Fig. 2 is an exterior, and Fig. 3 is an interior end elevation, of my car. Fig. 4 is a detached view, showing the vertical door-post, the door proper being cut in vertical section, and Fig. 5 is a plan view of the end of my car, the top part thereof being broken away about on line x - x ; 35 Fig. 2; and Figs. 6 and 7 are detail views of the doors or gangways.

In the drawings I have omitted the side and end slats common to stock-cars, in order to more clearly illustrate my invention.

40 In carrying out my invention I construct the cars A with the end doorways or openings a . At the base of this doorway, and near the opposite sides thereof, I secure staples a' , which form a part of the hinge of platform B. This 45 platform B is made nearly the width of the doorway a , and is provided near its lower end with strap-hinges b , eighteen inches long. The object of straps eighteen inches long is that either end of platform may turn out and be easily passed under the other platform-hinge. They are to be made fast to platform with one

bolt at top end of hinge and half-way up the side of platform, which project into the staples a' , and secure the platform to the car, so it can be swung vertically outward from the position 55 shown in Fig. 2 to that shown in Fig. 1. These staples a' are made of a sufficient length to permit the elevation of the lower end of the platform to allow the sweeping thereunder of the filth accumulating in the car. This platform, 60 when not in use, is held up in the doorway by the bar b' , which is hinged at one end to the vertical beam a^3 , and is passed across the doorway-opening, and is secured at its other end to the beam a^3 by hasp b^2 and staple b^3 , as shown in 65 Fig. 2. The door C is composed of the door-post c and the door proper, c' . The post c is journaled vertically at one side of the door-opening a , close to the beam a^3 , and has the slat or bar c^2 , secured to the post by blocks c^3 , or 70 in other suitable manner, to provide ways or guide-slots for the rails or bars c^4 of the door proper. This door proper is composed of the bars c' and the end battens, c^5 . The door c' is secured to the post by placing its bars c^4 in the 75 slots or ways of the post, so that it can be swung with the said post and moved laterally along the same, as indicated in Figs. 3 and 5. This door proper is provided on its outer end with hook c^6 in position to engage in the eye c^7 , secured on the beam a^2 at one side of the doorway. 80

In the operation of the device, when the several parts are in the position shown in Fig. 2, the doorway is closed, locking the car, and in Fig. 1 the several parts are shown arranged to 85 permit the stock to pass from one car into another in loading the train. To secure this arrangement, the bar b' is unlocked from staple b^3 and let down, releasing platform B, which turns down against the floor or the platform 90 from adjacent car, as shown in Fig. 1. The door C is then unlatched, pushed back slightly to enable its outer end to escape the beam a^2 . It is then swung outward and across the space between the adjacent cars, and its hook c^6 , engaging the eye c^7 of adjoining car, provides a 95 side wall for one side of the gangway between the cars, and the door from the other car, being swung and secured in similar manner, provides a way for the other side of the passage-way, so that the stock can pass safely from car to car.

It will be understood that good results will be obtained by the use of the platform alone without the side walls or guards; (also, that only one of adjacent cars need be provided with the platform.) The door, also, where so desired, might be made without the sliding movement described, with its outer end arranged so as to escape the beam a^2 , and connected thereto in suitable manner; but I prefer the construction as shown and described, as thereby a stronger, safer, and better device is provided. By the use of the sliding gate it will be seen it is, when closed, firmly supported against the inner face of the beam a^2 , and in the operation of opening the same it can be moved back slightly, practically in line with the end of the car, and is then swung outwardly, as described. It will be seen that this movement would not interfere with cattle packed in the cars in the usual way, and could be readily accomplished. By this manner of connecting the cars the train could be filled from one end, the cattle or other stock passing through the intermediate to the farthest car until it is full, when the next car is filled, and so on till the train is loaded. Each car as it is filled can be locked, as shown in Fig. 2. Where so desired, the train can be filled from any point along the same by providing side doors in the cars, opening at the loading-point. This avoids the moving of the train as each car is filled or the moving of the stock-loading devices from point to point along the train.

The doors and doorways and platform are to be made any desirable width, but not less than three nor more than six feet, with upper and lower doors and platforms for double-deck cars.

Having thus described my invention, what I claim, and desire to secure by Letters Patent, 40 is—

1. In a stock-car having an end doorway, the combination of the said car, a gangway-platform hinged at the base of said doorway and turning outward, the post c , journaled vertically at one side of the said doorway, and the door supported on said post, substantially in the manner described, whereby it may be moved longitudinally along and swung with said post, and adjusted to close the car-doorway or serve as a side guard to the gang-platform, as and for the purposes specified. 45

2. The combination of the car having end doorway, the door hinged at one side of said doorway and provided with a suitable latch at its outer end, the gangway-platform hinged at one end in the base of said doorway and adapted to be turned vertically outward or up against the door, and the locking-bar pivoted at one end on the car and swung across in front of platform B, and secured at its other end by means of hasp and staple, substantially as described, and for the purposes specified. 55

3. In a stock-car, the combination, with the car having doorway and provided with staples a' , arranged on opposite sides of said doorway, of the platform B, and straps b , having their upper ends pivoted to the sides of the platforms and their lower ends bent laterally and extended into the staples a' , the said staples and straps serving as a hinge for the platform, and also to permit its elevation, substantially as described, and for the purpose specified. 65

In testimony whereof I affix my signature in presence of two witnesses.

MARION H. WALKER.
